L. J. TAYLOR

APPARATUS AND METHOD FOR COOLING CARBONATED WATER

Filed Oct. 15, 1924

Inventor

Lee T. Taylor,

By Clarissa A. D. Brown

Attorney

UNITED STATES PATENT OFFICE.

LEE J. TAYLOR, OF NEW BERN, NORTH CAROLINA.

APPARATUS AND METHOD FOR COOLING CARBONATED WATER.

Application filed October 15, 1924. Serial No. 743,763.

This invention relates to improvements in means for cooling the water of a carbonator and has for its principal object to provide a simple and efficient apparatus and method 5 which will at all times be positive and efficient in cooling the water of a carbonator.

One of the important objects of the present invention is to provide a means whereby the water in the carbonator will be initially 10 cooled as the same is delivered to the carbonator, additional means being provided for keeping the water therein in a cold state.

A further object of the invention is to 15 provide an apparatus of the above mentioned character, which is simple in construction, inexpensive, strong and durable and furthermore adapted for the purposes for which it is designated.

Other objects and advantages of this 20 invention will become apparent during the course of the following description.

In the accompanying drawing forming a 25 part of this specification and in which like numerals designate like parts throughout the same:

The figure represents a side elevation of 30 the apparatus embodying my invention showing the manner in which the same is associated with the carbonator.

In the drawing wherein for the purpose 35 of illustration is shown the preferred embodiment of my invention, the numeral 1 designates generally a carbonator of any well known construction, the same including the receptacle 2 supported on a suitable base 3. An elongated neck 4 extends upwardly from the top of the receptacle and communicates therewith in the usual manner. A closure cap 5 is positioned on the top of the neck 4 and furthermore supports the nozzle 6 which is associated with the water line 7. The gas line 8 extends into the upper portion of the receptacle 2 in the usual manner while the carbonated water is adapted to be discharged from the receptacle 2 through the pipe 9. For the purpose 45 of cooling the water in the carbonator 1, I provide an apparatus the construction of which will be presently described.

The apparatus includes a suitable brine tank 10 which is supported on the standards 11 and is open at its top. The tank is

adapted to be filled with brine. An outlet pipe 12 extends from the tank 10 adjacent the bottom thereof and has communication with a suitable centrifugal pump designated generally by the numeral 13. A brine circulating pipe 14 extends from the centrifugal pump 13 into the receptacle 2 of the carbonator 1 and a suitable coil 15 is formed in the brine line 14 and is disposed within the bottom of the receptacle as clearly shown in the drawing. The brine line 14 then extends upwardly in the receptacle and a closely wound coil 16 is formed therefrom and is arranged within the neck 4 for the purposes to be presently described. The opposite end of the brine line 14 extends through the cap or closure 5 and communicates with the return pipe 17, the latter having its discharge end disposed within the top of the brine tank 10.

The brine in the tank 10 is kept cool by placing therein the ammonia circulating coil 18. The ammonia is supplied to the coil 18 by means of a suitable pipe 19 which extends from the bottom of a suitable ammonia receiver and condenser 20. The water pipe 21 extends through the ammonia receiver and condenser 20 in the usual manner. After the ammonia in the coil 18 has expanded, the same is discharged through the pipe at 22 into a suitable ammonia compressor designated generally by the numeral 23 and as the latter may be of any well known construction, a further detailed description thereof is not thought necessary. The ammonia is then again compressed and returned to the ammonia receiver 20 where it again may be used.

In operation, the plain water entering the carbonator 1 through the pipe 7 will enter the top of the neck 4 in a spray and the cold brine circulating through the coils 16 will contact with the plain water whereby the same will be initially cooled before entering the receptacle 2. When the water enters the receptacle 2 and is carbonized in the well known manner, the coils 15 through which the cold brine circulates will keep the carbonated water in a cold state at a suitable temperature. The freezing of the carbonated water will be prevented by using a water cooling means of the above mentioned character, wherein the brine circulating coil

is disposed directly within the carbonator, the water will be kept at the desired temperature regardless of how long the carbonator is not in operation.

While I have shown the preferred embodiment of my invention, it is to be understood that various changes in the size, shape and arrangement of parts may be resorted to without departing from the spirit of the 10 invention and the scope of the appended claims.

Having thus described my invention, what I claim is:—

1. An apparatus for cooling carbonated 15 water including a carbonator having a water inlet at its top and a water outlet at its bottom, a relatively large cold brine circulating coil located wholly within the top of the carbonator, a relatively small cold brine cir- 20 culating coil located wholly within the bottom of the carbonator, means in the carbonator connecting the coils, the large coil having its terminal passing through the upper portion of the carbonator to the ex- 25 terior and the terminal of the relatively

small coil extending through the bottom portion of the carbonator to the exterior and a gas line entering the carbonator between the coils.

2. An apparatus for cooling carbonated 30 water, including, in combination, a carbonator including a lower enlarged portion having an outlet at its bottom and an upper restricted portion having an inlet at the top thereof for water to be carbonated, a relatively large brine coil located wholly in the upper portion of the carbonator and having its upper terminal extending through an opening in the top portion of the upper restricted portion of the carbonator, a relatively small brine coil located in the lower portion of the carbonator and having its terminal extending through an opening in said lower portion of the carbonator, means 40 in the carbonator connecting the two coils and a gas line entering the lower enlarged portion above the relatively small coil.

In testimony whereof I affix my signature.

LEE J. TAYLOR.
